UNITED STATES PATENT OFFICE.

ARTHUR CRYER, OF PHILADELPHIA, PENNSYLVANIA, ASSIGNOR TO LEWIS & BROTHER, OF SAME PLACE.

DESIGN FOR A BAR-FIXTURE.

SPECIFICATION forming part of Design No. 23,142, dated March 20, 1894.

Application filed February 7, 1894. Serial No. 499,410. Term of patent 7 years.

To all whom it may concern:

Be it known that I, ARTHUR CRYER, a citizen of the United States, residing in Philadelphia, Pennsylvania, have invented a certain 5 Design for Bar-Fixtures, of which the following is a specification.

My design for a bar fixture is fully illustrated in the accompanying drawings in which—

10 Figure 1, is a front view of the fixture; and Fig. 2, is an end view.

The main feature of the design is a bar fixture having the projecting cornice supported by columns, the ceiling of the cornice being 15 flat at the center and rounded at each end.

A is the side-board portion.
B is the counter and beyond each end of the counter are posts D, D resting on the floor.
E is projecting cornice extending from the 20 rear to a point above the counter and from end to end of the structure; the rear portion of the cornice is supported by the framing F and the front by the posts D D which extend to the floor. The central portion e of the ceil-

ing of the cornice is flat and the end portions 25 are curved as shown, producing a deep panel E' at each side as shown in Fig. 2. The flat and curved portions of the ceiling are paneled and within the panels are mirrors.

The prominent features of the design are, 30 first, the projecting cornice having a flat center and curved ends, second, the illuminating panels in the ceiling of said cornice, third, the deep panels at each end and fourth, the columns supporting the cornice extending from 35 the cornice to the floor.

I claim—

The design for a bar fixture as herein described and shown in the accompanying drawings. 40

In testimony whereof I have signed my name to this specification in the presence of two subscribing witnesses.

ARTHUR CRYER.
